UNITED STATES PATENT OFFICE.

DANA WILLIS POND, OF PROVIDENCE, RHODE ISLAND, ASSIGNOR TO DIAMOND MACHINE COMPANY, OF PROVIDENCE, RHODE ISLAND, A CORPORATION OF RHODE ISLAND.

METAL-WORKING MACHINE.

1,090,342.

Specification of Letters Patent. Patented Mar. 17, 1914.

Application filed May 29, 1913. Serial No. 770,609.

To all whom it may concern:

Be it known that I, DANA W. POND, a citizen of the United States, and resident of the city of Providence, in the county of Providence and State of Rhode Island, have invented certain new and useful Improvements in Metal-Working Machines, of which the following is a specification.

This invention relates to metal working machines especially of that type having a slow moving table, such as a grinding machine or the like, and the object of the invention is to provide auxiliary power transmitting means driven by the machine and controlled in its action by mechanism operated at the end of the table travel in each direction, whereby said power means is released to act upon the driving mechanism and reverse the direction of the table travel.

A further object of the invention is to provide a shiftable cam plate operated by the reversing mechanism so arranged that it will throw one of the driving belts from the tight pulley onto the loose pulley before moving the second belt from the loose pulley onto the tight pulley, so that both belts which drive in opposite directions cannot possibly engage opposite edges of the tight pulley at the same time, thereby preventing wearing of the belts from this cause and obviating the usual squeaking and shrieking noises which usually accompany the shifting of the belts from tight to loose pulleys.

With these and other objects in view, the invention consists of certain novel features of construction as will be more fully described and particularly pointed out in the appended claims.

Of the accompanying drawings: Figure 1— is an end elevation of a grinding machine to which my improved device is attached. Fig. 2— is a front elevation of the machine showing the table carrying the dogs which move the controlling mechanism at the end of each stroke of the table. Fig. 3— is a perspective view showing the general arrangement of the reversing mechanism. Fig. 4— is a front elevation partly in section, illustrating my improved reversing mechanism. Fig. 5— is an end view of the reversing mechanism showing the casing in section. Fig. 6— is a plan view of the mech-

anism showing the rocker arm and the dogs carried by the table for actuating said rocker arm to control the movement of the shifting mechanism. Fig. 7— is a perspective view illustrating the cam plate by means of which one belt is shifted before or in advance of the other to prevent the engagement of both at the same time with the tight pulley. Fig. 8— is an end view illustrating the stop mechanism of the table for controlling the position of the cam whereby both belts are moved onto the loose pulleys to arrest the action of the table. Fig. 9— is a detail of the gear train for reciprocating the work table.

Referring to the drawings the work carrying table 10 is mounted to slide on suitable ways 11 on the base portion 12. This table is provided with dogs 13 and 14 which are adjustable lengthwise of the table in the groove 15 in its outer edge and set in any desired position to control its stroke or length of travel. The working tool in this particular case is shown as being a grinding wheel 16 and is mounted in the casing 17 on the main shaft 22 and driven by the motor 18 through the pulleys 19 and 20 by means of the belt 21 and the power for driving the table is transmitted from the main shaft 22 to the jack shaft 24 through the belt 25 and thence from jack shaft 24 to drive shaft 26 through straight and cross belts 27 and 28 which extend through the rear base portion 29 of the machine over tight and loose pulleys 57, 58 and 60. This driving shaft 26 is journaled in bearings 82 and 83 in the lower half of the pulley casing 84 and extends forward through the table supporting base portion 12 and has mounted thereon a train of gears as illustrated in Fig. 9 which lead up to and engage the rack 30 on the lower side of the table and through which train the table is driven at a comparatively slow speed, so slow that it is found very difficult in practice to shift the belts by a direct connection actuated by the dogs as is customary in quicker action reciprocating tables, such as planer machine tables and the like. Therefore I have provided auxiliary means merely controlled by the table movement to positively throw the belts and reverse the direction of travel of the table, said means being described as follows: This shifting

mechanism, as best illustrated in Fig. 4, comprises a sleeve 31 which is loosely mounted for convenience on the shaft 26, which sleeve has a cam 32 secured thereto by means of keys 33. The inner end of this sleeve is provided with an enlarged shoulder 34 between which and an outer collar 35 the hub 36 of the pulley 37 may rotate under friction. This outer collar 35 is provided with a hub 10 portion 38 which is keyed at 39 to the sleeve 31 so as to render more effective the frictional action of the rotating pulley on the sleeve when the collar 35 is set up to regulate the frictional tension on the pulley hub, 15 by means of the threaded nut 40. This cam 31 is provided with a cam groove 41 which is engaged by a pin 42 on the yoke 43, the latter being pivoted at 44 in the bracket 45 below. To the inner arm 46 of this yoke is 20 pivoted the link 47, the opposite end of said link being connected at 48 to the cam plate 49 mounted to slide longitudinally in guides 50. This cam plate is provided with angular slots 51 and 52 which are engaged by guide 25 pins 53 and 54 respectively, said guide pins extending into said slots from offset portions of the belt shifting arms 55 and 56 respectively, said arms being pivoted at 57 and 58. The angular extensions of these cam grooves 30 are such that when the plate is moved to the right its first action is to throw the outer end of arm 56 to the left so as to move the cross belt 28 which it guides, from the tight pulley 57 onto the loose pulley 58, and by a little 35 further movement in the same direction this plate moves the arm 55 to the left and throws the belt 27, by means of its guide eye 59, from the loose pulley 60 onto the tight pulley 57. In order to control the movement of 40 this cam 31 so that it will work only at the end of the table stroke I have provided stop lugs 61 and 62 constructed preferably of hardened steel and firmly secured to opposite ends of the barrel of the cam. I have then 45 mounted an abutment plate 63 to be reciprocated longitudinally in the bearing 64 and have secured said plate to the connecting rod 65. This connecting rod extends through the table base 12 and is provided 50 with an upwardly extending pin 66 on its forward end. This pin 66 is engaged by one end of a rock arm 67 which is pivoted at 68 to a bracket 69 on the side of the base 12, and the opposite end of this rock arm is provided 55 with an upwardly extending pin 70. One of the dogs 14, secured to the table 10, is provided with an inwardly beveled face 71, while the opposite dog 13 is provided with an outwardly beveled face 72, whereby 60 when the table moves to the left the face 71 of the dog 14 throws the pin 70 inward to its position illustrated in Fig. 6 and draws the connector 65 and abutment plate 63 outward, see Fig. 4, in position to engage the

stop lug 61. When the movement of the 65 table has been reversed and approaches the opposite end of its stroke, the pin 70 engages the oppositely beveled face 72 of the dog 13 moving the connector 65 and its plate 63 inward out of engagement with the stop 70 lug 61, and into engagement with the stop lug 62, thereby permitting the cam to be rotated by means of friction from the rotating pulley hub half a revolution.

The groove 41 in the cam 31 is so shaped, 75 that when it is on a half stroke or a quarter revolution, both of the belts 27 and 28 will be on their loose pulleys 58 and 60, therefore when it is desired to stop the table I have arranged to arrest this cam in its mid- 80 way position by means of a stop latch 73 which is pivoted at 74, see Fig. 8, said latch being provided with an overhanging lip 75, whereby when this latch is moved up into vertical position, as shown in Fig. 8, one of 85 the lugs 61 or 62, the first to approach the same after the latch has been positioned, will engage this overhanging portion and stop the cam on its quarter stroke or revolution, throwing both of the belts onto the 90 loose pulleys and the table immediately stops its travel. In order to retain this latch in its stopped position I have provided a lock lever 76 which is provided with a notch 77 adapted to engage the pin 78 on the side 95 of the latch. The lock is pivoted at 79 and has an operating handle 80.

The operation of my improved belt fastening mechanism may be further described as follows: In order to secure a positive shifting 100 mechanism of simple construction I have provided a pulley 37 driven continuously by belt 85 from jack shaft 24. The hub 36 of this pulley runs between two friction collars 34 and 35 which are adjustable to regulate the amount 105 of frictional driving power to be exerted on the cam 32 through the sleeve 31. This cam is provided with two stop lugs mounted practically on opposite halves thereof and is controlled in its rotation by engagement of 110 said lugs with an abutment plate, whereby when said plate is moved out of engagement with one stop lug it is carried across into position to engage the opposite lug thereby releasing the cam and permitting it to make 115 a half revolution before it again brings up against said plate. This half revolution, as has been shown, is sufficient to move the cam plate 49, through the yoke 43 and connecting rod 47, to the right, from the position 120 illustrated in Fig. 4, so as to throw the belt engaging arm 56 to move its cross belt from the tight pulley 57 to the loose pulley 58, and subsequently to move the arm 55 to throw its straight belt 27 from the loose 125 pulley to the tight pulley 57, thereby reversing the direction of travel of the work table. The dogs 13 and 14 of course may re-

ceive relative adjustment into any position along the side of the table, so as to regulate the length of table stroke, and then when either of these dogs engages the pin 70 on the 5 rock arm 67 the abutment plate is moved to its opposite position, the cam permitted to rotate a half revolution, the belts shifted from one position to another and the direction of travel of the table reversed.

I claim:

1. In a machine of the character described, a reciprocable work table, driving means therefor, a tool for operating upon work carried by said table, and auxiliary power 15 transmitting means actuated by said driving means and independently of said table the same being controlled indirectly by the movement of the table for reversing the direction of table travel.

2. In a machine of the character described, a reciprocable work table, driving means therefor, auxiliary power transmitting means actuated by said driving means and independently of said table, and means actuated by the table at the end of its travel in each direction to release said transmitting means and permitting the same to reverse the direction of travel of the table.

3. In a machine of the character described, 30 a reciprocable work table, driving means therefor, and auxiliary power transmitting means including a power driven cam controlled in its action by the movement of the table for reversing the action of said driving means at each end of the table stroke to move the table in the opposite direction.

4. In a machine of the character described, a reciprocable work table, driving means therefor, a tool for operating upon work carried by said table, and auxiliary power transmitting means including a frictionally driven cam controlled in its action by the movement of the table for reversing the action of said driving means at each end of the 45 table stroke.

5. In a machine of the character described, a reciprocable work table, driving means therefor, a tool for operating upon work carried by said table, a continuously driven 50 member, a rotatable cam under constant frictional tension by said member, means for controlling the time and amount of rotation of said cam, and means whereby said controlling means is actuated by the movement 55 of the table at the end of its stroke in either direction.

6. In a machine of the character described, a reciprocable work table, driving means therefor, a tool for operating upon work carried by said table, and auxiliary power transmitting means actuated by said driving means and independently of said table controlled indirectly by the movement of the 60 table for reversing the direction of table travel, and means for rendering said driving means inoperative.

travel, and means for rendering said driving means inoperative.

7. In a machine of the character described, a reciprocable work table, driving means therefor, auxiliary power transmitting means actuated by said driving means and independently of said table, and means actuated by the table at the end of its travel in each direction to release said transmitting means and permitting the same to actuate the driving means to reverse the direction of 75 travel of the table, and means for rendering said driving means inoperative.

8. In a machine of the character described, a reciprocable work table, driving means therefor, and auxiliary power transmitting 80 means including a friction driven cam controlled in its action by the movement of the table for reversing the action of said driving means at each end of the table stroke, and means for rendering said driving means inoperative.

9. In a machine of the character described, a reciprocable work table, driving means therefor, a continuously driven member, a friction driven cam for operating the reversing mechanism and acted upon by said member to be rotated when released, means acted upon by the moving table for releasing said cam at the end of each table stroke to reverse the direction of table travel, and a latch for 95 arresting the said cam at a predetermined portion of its stroke to disconnect the driving means and render the same inoperative.

10. In a machine of the character described, a reciprocable work table, driving 100 means therefor, a continuously driven member, a friction driven cam for operating the reversing mechanism and acted upon by said member to be rotated when released, means acted upon by the moving table for 105 releasing said cam at the end of each table stroke to reverse the direction of table travel, and means for rendering said driving means inoperative.

11. In a machine of the character described, a reciprocable work table, driving means therefor, a continuously driven member, a friction driven cam for operating the reversing mechanism and acted upon by said member to be rotated when released, 115 means acted upon by the moving table for releasing said cam at the end of each table stroke to reverse the direction of table travel, and a latch for engaging said cam at a portion of its revolution to render the driving 120 means inoperative.

12. In a machine of the character described, a reciprocable work table, driving means therefor, a cam, means for rotating said cam by friction, a reciprocable plate 125 positioned by said cam, means in said plate for controlling the action of said driving means, and means actuated by the movement

- of said table for controlling the action of said cam to position said plate to reverse the direction of travel of said table at the end of each stroke.
- 5 13. In a machine of the character described, a reciprocable work table, a straight and a cross belt for driving said table in opposite directions, a cam friction driving means therefor, reciprocable means posi-

tioned by said cam for shifting said belts one 10 in advance of the other, and means actuated by the table for controlling the cam action.

In testimony whereof I affix my signature in presence of two witnesses.

DANA WILLIS POND.
